DESIGN FOR A BABY CARRIAGE

Karl E. Ewald, Chicago, Ill.

Application July 24, 1944, Serial No. 114,539

Term of patent 7 years

(Cl. D14—14)

To all whom it may concern:

Be it known that I, Karl E. Ewald, a citizen of the United States, residing at Chicago, in the county of Cook and State of Illinois, have invented a new, original, and ornamental Design for a Baby Carriage, of which the following is a specification, reference being had to the accompanying drawing, forming a part thereof.

In the drawing:

Fig. 1 is a side view of a baby carriage, showing my new design;

Fig. 2 is a top plan view; and

Fig. 3 is a rear elevational view thereof.

The characteristic features of the present design are shown in full lines on the drawing.

I claim:

The ornamental design for a baby carriage, substantially as shown and described.

KARL E. EWALD.
